United States Patent Office

Des. 222,556
Patented Nov. 2, 1971

222,556

FLOODLIGHT OR THE LIKE

William R. Mattson, Gloucester, and Ruth G. Petersen,
Medfield, Mass., assignors to Sylvania Electric Products
Inc.

Filed Sept. 9, 1970, Ser. No. 24,904

Term of patent 14 years

Int. Cl. D26—03
U.S. Cl. D48—20

FIG. 1

FIG. 2

Des. 222,556

PAGE 2

FIG.3

FIG.4

FIG. 5

FIG. 6

FIG. 1 is a side elevational view of the floodlight or the like showing our new design;

FIG. 2 is an opposite side elevational view thereof;

FIG. 3 is a top plan view thereof;

FIG. 4 is a bottom plan view thereof;

FIG. 5 is a rear elevational view thereof;

FIG. 6 is a front elevational view thereof.

The cord and bracket are shown in broken lines in FIGS. 1 through 6 for illustrative purposes only.

We claim:

The ornamental design for a floodlight or the like, as shown and described.
